(57) CLAIM

The ornamental design for a drinking glass, as shown and described.

DESCRIPTION

FIG. 1 is a perspective top view of a drinking glass;

FIG. 2 is a side elevation view thereof;

FIG. 3 is an enlarged top view thereof; and,

FIG. 4 is an enlarged bottom view thereof.

The portions of the drinking glass shown in broken lines form no part of the claimed design.

1 Claim, 4 Drawing Sheets
